CARBURETOR

Judson Williams, Philadelphia, Pa.

Application July 10, 1945, Serial No. 604,238

6 Claims. (Cl. 261—61)

1

This invention relates particularly to a carburetor for a portable motor-generator unit of the character wherein a small two-cycle engine is employed to drive a correspondingly small electric generator.

An object of the invention in this connection is to provide a carburetor embodying a block having a carbureting passage therein, and wherein novel choke and throttle valves will be assembled upon said block in a novel manner to regulate the flow of air and fuel mixture through said passage.

A further object of the invention is to provide a unit wherein the engine crank case will be provided with a removable end plate which carries the carburetor block mentioned, wherein the intake valve will be journaled through the plate upon the block, and wherein by removing said plate, the plate, valve and block may be displaced as a unit.

Other and incidental objects of the invention will appear during the course of the following description, and in the drawings:

Figure 1 is a perspective view of my improved unit.

Figure 2 is an end view of the unit.

Figure 3 is a vertical section through the carburetor block and associated parts.

Figure 4 is a horizontal section through said block and associated parts including parts of the engine.

Figure 5 is a vertical section through a portion of the engine and fan.

Figure 6 is a perspective view of the carburetor block and parts associated therewith, the parts being separated but in proper relative position.

Figure 7 is a transverse detail section through the carburetor block at one of the valve sockets therein.

Referring now more particularly to the drawings, I employ an oblong cage 9 which is formed of suitable side, end and bottom bars all rigidly secured together. The cage is preferably of aluminum to save weight.

Mounted within the cage at the top thereof and near one end of the cage is a fuel tank 10 connected with a float bowl assembly, indicated as a whole at 11, said assembly being located near the opposite end of the cage at the bottom thereof. The assembly 11 has been made the subject of a separate application filed December 17, 1947, Serial No. 792,175 now Patent No. 2,492,123 issued December 20, 1949.

The assembly 11 is mounted upon one end plate of the crank case of an engine, indicated as a

2

whole at 12, and this plate also serves as the end plate of the housing of a fan, indicated as a whole at 13, the fan serving to cool the cylinder of the engine, as will all be later explained in detail. Connected with the engine cylinder is an exhaust port assembly, indicated as a whole at 14. This assembly forms the subject of Patent No. 2,418,741 issued to me April 8, 1947.

Mounted upon a suitable base plate beneath the tank 10 is an electric generator 15 connected with the engine by a belt 16, the base plate being secured to the bottom bars of the cage. The generator may be of any approved character.

It is to be noted that all parts lie within the lines of the cage to be protected thereby, and, preferably, aluminum is used throughout, where possible, so as to gain minimum weight.

As best brought out in Figures 4 and 5 of the drawings, the engine 12 includes a cylindrical crank case 17 to which is appropriately attached a cylinder 18 having a liner 19 therein, and removably connected to one end of the crank case is an end plate 20 having a hub 21 fitting in the crank case. The hub 21 mounts a bearing 22 through which is journaled a crank shaft 23 on the inner end of which is fixed a cheek plate 24, and mounted on said plate is a crank pin 25 provided at its ends with like studs one of which is fixed to the cheek plate and the other of which, indicated at 26, is free. Sealing the hub 21 of the end plate 20 is a suitable gland 27.

Reciprocal in the engine cylinder 18 is a piston 28 carrying a connecting rod 29 the large end of which engages the crank pin 25, and closing the cylinder at its upper end is a removable head 30 which carries a protecting cap 31 for the usual spark plug. The cylinder 18, liner 19, and piston 28 are all of aluminum and the assembly has been made the subject of a separate application filed October 2, 1945, Serial No. 619,792.

As best seen in Figures 1 and 2 of the drawings, the end plate 20 of the crank case 17 is enlarged and shaped to also provide a removable end plate for a fan housing 32 on which is formed a discharge duct 33, and mating with said duct is a detachable outlet 34 which embraces the engine cylinder 18 at its upper end portion. The outer end wall 35 of the housing is provided centrally with openings 36 to admit air and is also ribbed to provide reinforcement for a socket 37, and fitting in said socket is a bearing 38 for the outer end portion of the crank shaft 23. Fixed to said shaft are blades 39 which, while the engine is in operation, function to impel a blast of air through the duct 33 and outlet 34 about the upper end

portion of the engine cylinder 18 for cooling the same. Fixed to the outer end of the crank shaft 23 is a pulley 40 accommodating the belt 16 which drives the generator 15 and, preferably, said pulley is grooved to receive the usual detachable cord which may be wound about the pulley and operated in the customary manner for starting the engine, as will be well understood.

Detachably connected to the crank case 17 of the engine opposite the end plate 20 is an end plate 41 having a hub 42 which fits in the crank case, and integrally formed on said plate to extend parallel therewith is a carbureter block 43 which is provided with a cylindrical valve chamber 44 extending axially of said plate. Closing the valve chamber at its outer end is a press-fit cap 45. Formed through the block is a carbureting passage 46 at the inner end of which is a reduced port 47 entering the valve chamber 44, and rising from the block at its outer end portion is a flat post 48. Connected to the outer end of the block to communicate with the passage 46 is a detachable air filter 49, the details of which are unimportant.

It is now to be noted that the engine 12 is a two-cycle engine the operation of which will be well understood, and journaled in the valve chamber 44 to control the admission of fuel mixture to the crank case 17 is a hollow intake valve 50 having a port 51 to register with the port 47 of the passage 46. Fixed to the inner open end of said valve is a cheek plate 52 matching the cheek plate 24 of the crank shaft 23, and formed in the cheek plate 52 is a notch 53 which snugly but removably receives the stud 26 of the crank pin 25. The valve is thus coupled with the crank shaft by a direct, freely separable connection which will serve to rotate the valve in time with the crank shaft while, however, the valve may be withdrawn and removed with the end plate 41 of the crank case and carbureter block 43. Furthermore, it is to be noted that the crank shaft will be wholly supported by the bearings 22 and 38, which bearings will sustain the thrust of the connecting rod 29 on the crank pin 25, so that the valve 50 will turn free of all load on the crank shaft. After the end plate 41 has been removed, the valve may, of course, be readily withdrawn. Thus, a new valve may be readily substituted for a valve which has become worn.

Frictionally fitting in the passage 46 of the carbureter block 43 is a Venturi sleeve 54 located about midway between the ends of said passage, and extending through the block and through said sleeve diametrically of the latter is a slidably removable nozzle tube 55 to which is fixed a stop plate 56 abutting the lower side of the block. Detachably connecting the tube with the block is a screw 57 engaged through said plate. The tube is formed at the lee side thereof with a fuel orifice 58 located axially of the sleeve 54, and connecting the lower end of said tube with the float bowl assembly 11 is a flexible hose 59 so that liquid fuel will be supplied to the tube as it is used therefrom.

Screwed over the upper end of the nozzle tube 55 to abut the upper side of the block 43 is a head 60, and screwed through the upper end of said head is a needle valve 61, the reduced lower end portion of which projects into said tube, the valve being rotatably adjustable to position the tapered lower tip thereof relative to the orifice 58 for regulating the discharge of liquid fuel therefrom. Detachably connected to the upper end of the valve is a knob 62 which is recessed

at its lower side to freely receive the reduced upper end portion of the head, and screwed into the knob is a stop pin 63 which projects at its lower end below the knob to contact the post 48 for limiting the adjustment of the valve in opposite directions. Interposed between the block 43 and the knob is a spring 64 adapted to eliminate any vertical play in the valve, and attached to the post 48 is a detent spring 65, the free end of which bears against the ribbed periphery of the knob for yieldably locking the valve in adjusted position.

As will now be seen, when the port 51 of the intake valve 50 registers with the port 47 at the inner end of the passage 46 of the carbureter block 43, air will be drawn in through the filter 49 and through said passage to flow around the nozzle tube 55 at the area of the orifice 58. Accordingly, as will be well understood, fuel will be drawn through said orifice to mingle with the air supply and form a fuel mixture within the inner end portion of said passage, from whence the mixture will be drawn through the intake valve 50 into the engine crank case. In this connection, it is to be noted that the displacement of the engine is very small, in fact, slightly less than a cubic inch. For this reason, the parts of the carbureter are correspondingly small, and only a very slight adjustment of the needle valve 61 is necessary to produce a very pronounced change in the character of the fuel charge. Figures 3, 4, and 5 of the drawings show the parts full size.

At equally spaced points on opposite sides of the plane of the nozzle tube 55, the carbureter block 43 is recessed at its forward side to provide like sockets 66, one of which is shown in enlarged detail in Figure 7. As will be observed, the sockets are provided with flat bottom walls 40 which almost touch the periphery of the passage 46 at a tangent thereto to define feathered webs 67, and formed through said webs in a horizontal plane with the axis of the passage are openings 68.

In conjunction with the sockets 66, I provide a pair of like butterfly valves, one of which, indicated as a whole at 69, provides a choke valve, and the other of which, indicated as a whole at 70, provides a throttle valve. These valves include stems 71, and fixed to the forward ends 50 of said stems are valve disks 72, the peripheries of which project beyond the forward terminals of the stems. Thus, as the valves are assembled upon the block 43, the disks may, upon being disposed horizontally, be pushed through the feathered webs 67 puncturing the same, when the stems 71 will enter the openings 68 so that the disks may be disposed within the passage 46. The valve disks will thus form their own slots 73 in said webs, and by mounting the disks on the ends of the stems and feathering the webs, the necessity for milling said slots through the webs is eliminated.

Journaling the valve stems 71 are bushings 74 which freely fit in the sockets 66 of the block 65 43 and are stepped to provide annular shoulders 75 from which rise nipples 76. Recessed to freely accommodate said nipples are knobs 77 screwed on the outer ends of the stems and, as will be noted, the inner ends of the knobs are partially 70 cut away to provide straight stop shoulders 78 which extend diametrically of the knobs. Preferably, the knob of the choke valve 69 carries a short lever 79 which may be readily grasped for rotating the valve.

Detachably coupling the valves 69 and 70 is

a clamping plate 80, the terminals of which are provided with notches 81 which fit the nipples 76 of the bushings 74 so that the ends of the plate abut the shoulders 75, and screwed into the plate are stubs 82, the heads of which are disposed for engagement by the shoulders 78 of the knobs 77 for limiting the rotative adjustment of the valves to open and closed positions. Abutting the plate 80 midway between the stubs is a sleeve 83 provided at its outer end portion with oppositely disposed longitudinal slots 84, and extending through said slots is a bowed detent spring 85, the angled ends of which bear against the ribbed peripheries of the knobs 77 for yieldably locking the valves in adjusted position. Extending freely through the bottom wall of the sleeve 83 and through the clamping plate 80 is a cap screw 86 which is screwed into the block 43 and rigidly secures all of the assembled parts in position.

As will be appreciated, the sleeve 83 is somewhat larger in diameter than the screw 86 but is centered on the screw by the bottom wall of said sleeve so that the spring 85 may extend over the screw to be supported thereby, and, as will now be seen, tightening of the screw will cause the head thereof to coact with the outer end of the sleeve for binding the ends of the clamping plate 80 against the shoulders 75 of the bushings 74 so that said bushings will be firmly held in the sockets 66 of the block 43 to rigidly support the valves 69 and 70. The construction is simple and provides for the removal of both valves and associated parts simply by removing the single screw 86.

To install the valves 69 and 70, the stems 71 thereof are arranged in parallel relation with the plate 80 therebetween, when the ends of the plate are engaged with the nipples 76 of the bushings 74. The valves are then turned until the disks 72 thereof lie horizontally, when the disks are inserted in the sockets 66 of the block 43. Forward pressure on the valves will then cause the disks to puncture the webs 67, following which the valve stems 71 will enter the openings 68 as the disks move into the passage 46, when the plate 80 may be pushed forwardly to seat the bushings 74 in said sockets. The spring 85 is next inserted in the slots 84 of the sleeve 83, when the cap screw 86 is inserted through the sleeve as well as through the plate 80 and screwed into the block 43.

It is believed that the operation of the carbureter will be readily understood. As will be noted, the valve 69 may be adjusted to regulate the intake of air into the passage 46 of the block 43, while the valve 70 may be adjusted to regulate the flow of fuel mixture into the crank case of the engine.

Having thus described my invention what I claim is:

1. A carbureter including a block having a carbureting passage therein, spaced rotatable butterfly valves mounted upon the block and having stems extending into said passage and provided with valve disks disposed within the passage, knobs carried by said stems, a single means detachably connecting the valves with the block, a sleeve carried by said means and provided with slots, and a detent spring bowed over said means to extend through said slots and yieldably engage said knobs.

2. A carbureter including a block having a carbureting passage therein, spaced butterfly valves having stems extending through a wall

of said passage and provided with valve disks disposed within the passage, bushings journaling said stems and abutting said wall but being freely removable therefrom, a separate clamping plate extending between the bushings externally of said wall and resting at its ends against said bushings, and means connecting the plate with said block and detachably securing the valves as well as the bushings and plate in position.

3. A carbureter including a block having a carbureting passage therein and provided in a wall of said passage with spaced external sockets, spaced butterfly valves having stems extending into said passage and provided with valve disks disposed within the passage, bushings fitting in said sockets and freely removable therefrom, said bushings journaling the valve stems and being provided with shoulders, a separate clamping plate extending between the bushings externally of said wall and notched at its ends to embrace the bushings resting against said shoulders, and means connecting the plate with said block binding the ends of the plate against said shoulders and detachably securing the valves as well as the bushings and plate in position.

4. A carbureter including a block having a carbureting passage therein, spaced rotatable butterfly valves mounted upon the block and having valve disks disposed within said passage, bushings journaling said valves and freely removable from the block, separate clamping means extending between said bushings externally of the block to rest at its ends against the bushings, and a single connecting means securing said clamping means to the block at a point between the valves binding said clamping means against said bushings and detachably connecting the valves as well as the bushings and clamping means with the block.

5. A carbureter including a block having a carbureting passage therein, spaced adjustable butterfly valves mounted upon the block and having stems extending into said passage and provided with valve disks disposed within the passage, adjusting knobs carried by said stems, bushings journaling said stems and freely removable from the block, separate clamping means extending between said bushings externally of the block to rest at its ends against said bushings, a single connecting means securing said clamping means to the block at a point between the valves binding said clamping means against said bushings and detachably connecting the valves as well as the bushings and clamping means with the block, and a single detent spring carried by said connecting means to yieldably engage at its ends with both knobs for holding the valves in adjusted position.

6. A carbureter including a block having a carbureting passage therein, spaced adjustable butterfly valves having stems extending through a wall of said passage and provided with valve disks disposed within the passage, knobs carried by said stems for adjusting the valves, bushings journaling said stems and abutting said wall but being freely removable from the block, a separate clamping plate extending between said bushings and resting at its ends thereagainst externally of said wall, a single screw securing said plate to the block at a point between the valves binding the plate against said bushings and detachably connecting the valves as well as the bushings and plate with the block, a sleeve carried by said screw and provided with slots, and a detent spring

bowed over said screw to extend through said slots yieldably engaging at its ends with both knobs for holding the valves in adjusted position.

JUDSON WILLIAMS.
